MILK CRATE

Jesus Luis Garcia Chavez, Privada Narciso Mendoza 97,
Ote. Torreon, Coahuila, Mexico

Filed Aug. 18, 1972, Ser. No. 281,777

Term of patent 14 years

Int. Cl. D9—03

U.S. Cl. D9—177

FIG. 3

FIG. 4

FIG. 1 is a side-elevational view of a milk crate showing my new design;

FIG. 2 is an end view thereof;

FIG. 3 is a top plan view; and

FIG. 4 is a bottom plan view of the milk crate. The side and end not shown are the same in appearance as the respective side and end shown.

I claim:

The ornamental design for a milk crate, substantially as shown and described.
